UNITED STATES PATENT OFFICE.

LEWIS CROOKE, OF NEW YORK, N. Y.

DESIGN FOR SHUTTER-BAR.

Specification forming part of Design No. 5,070, dated July 4, 1871.

To all whom it may concern:

Be it known that I, LEWIS CROOKE, of the city, county, and State of New York, have invented and produced a new and original Design in Shutter-Bars, of which the following is a specification:

Figure 1 is a side view of my shutter-bar, the parts being represented in the position they occupy when the shutter-bar is hooked or fastened. The form of the hook is shown in the dotted lines.

Fig. 2 is an under-side view of the same.

A is a bar, which connects the two plates B and C when the shutters or blinds are closed and fastened. This bar A is made of the form repre-

sented in the drawing, in which the face corners are shown as chamfered to give a more finished appearance. As a part of this design I mill or rib the middle portion of the plates B and C, as shown, and round the heads of the rivets or pins D and E, as represented.

I claim as my invention—

The design for shutter-bar, hereinbefore set forth and represented in the accompanying drawing.

LEWIS CROOKE.
